(57) CLAIM

The ornamental design for a ring for tie or scarf, as shown and described.

DESCRIPTION

The patent or application file contains at least one drawing executed in color. Copies of this patent or patent application publication with color drawing(s) will be provided by the Office upon request and payment of the necessary fee.

FIG. 1 is a first perspective view of a ring for tie or scarf, showing the new design;

FIG. 2 is a second perspective view thereof; and,

FIG. 3 is a front view thereof; the back view, the left side view, the right side view, the top view and the bottom view being identical thereto.
